UNITED STATES PATENT OFFICE.

WALLACE BRADLEY TYRELL, OF DELAVAN, WISCONSIN, ASSIGNOR TO BRADLEY KNITTING CO., OF DELAVAN, WISCONSIN.

SEAM FOR SEWED ARTICLES.

1,074,580.

Specification of Letters Patent. Patented Sept. 30, 1913.

Application filed March 14, 1910. Serial No. 549,361.

To all whom it may concern:

Be it known that I, WALLACE BRADLEY TYRELL, a citizen of the United States, residing at Delavan, county of Walworth, and 5 State of Wisconsin, have invented new and useful Improvements in Seams for Sewed Articles, of which the following is a specification.

My invention relates to improvements in 10 knit garments, and it pertains more especially, among other things, to the device for reinforcing and strengthening the seams and other parts of the garment which are subject to the greatest strain, whereby the 15 liability of such garment becoming stretched out of its normal shape is avoided.

My invention is further explained by reference to the accompanying drawings, in which—

20 Figure 1 represents a perspective view of a garment, the seams of which are provided with my reinforcing tape and tape retaining members. Figs. 2, 3, 4, 5 and 6 are all perspective views of a portion of the garment representing the same during the different steps of the process in the order taken 25 and by which my improvement is applied to the seams of a garment.

Like parts are identified by the same reference numerals throughout the several views.

1 and 2 in Fig. 2 represent the respective fabrics as they are arranged, preparatory to securing them together by a series of stitches 35 3. When the fabrics 1 and 2 have been thus secured together, as shown in Fig. 2, the marginal edge 4 is trimmed down on a line in close proximity to the series of stitches 3, when the fabrics are separated, as shown 40 in Fig. 3. When this is done, a piece of tape 5 is placed upon the marginal edges of the fabric, which has previously been stitched together as shown in Fig. 4, when said tape is stitched to the respective fabrics 1 and 2 by two series of stitches 6, 6. The two series of stitches 6, 6, are simultaneously formed by a sewing machine, which is provided with two needles and adapted 45 to form both series of stitches at the same time. Simultaneously with forming the se-

ries of stitches 6, 6, a piece of yarn 7, preferably of the same color as the fabric is automatically carried backward and forward across the tape in a zigzag direction, as shown in Fig. 5, with every stitch of 55 the series 6, 6, whereby such zigzag yarn is secured in place above the tape and whereby the tape is practically covered over and obscured from view. The tape 5 is preferably made of a strong, non-elastic 60 strip of cloth, which when thus secured to the garment, prevents the same from stretching at the points where it is subjected to the greatest strains, while the zigzag loops of yarn 7 practically obscure the tape from 65 view, whereby the garment is given a neat and finished appearance.

While my invention thus far described pertains to the manner of securing the tape to the garment above the seams, it is obvious 70 that if desired, the tape may be secured to the garment at any intermediate point between the seams or to garments in which there are no seams, whereby the garment at such point is prevented from being stretched 75 and drawn out of its normal symmetrical shape and whereby the garment is much more durable than it would otherwise be when subjected to the usual strains of wear. While for brevity of description, the rein- 80 forcing member 5 is referred to as a tape, it will be understood that any narrow strip of non-elastic fabric may be substituted therefor and that the same will come within the scope of my claim.

Having thus described my invention, what I claim as new, and desire to secure by Letters Patent, is—

In a seam for garments, the combination of two pieces of fabric secured together at 90 a distance from their edges by a series of stitches forming a seam, the marginal edges of such fabric being folded over upon itself in opposite directions, a reinforcing tape located above and upon said folded marginal edges, a continuous series of zigzag loops of yarn formed transversely to and upon the upper surface of said tape and extending in opposite directions past its respective edges, and a plurality of longitudi- 100

nal series of loop retaining stitches formed outside of and parallel with the respective edges of said tape, said parallel series of stitches being formed through the ends of 5 said zigzag loops and said fabric only, all substantially as and for the purpose specified.

In testimony whereof I affix my signature in the presence of two witnesses.

WALLACE BRADLEY TYRELL.
